UNITED STATES PATENT OFFICE.

JOHN H. DANIELS, OF NEW YORK, N. Y.

IMPROVEMENT IN DOOR AND WINDOW FASTENERS.

Specification forming part of Letters Patent No. **177,102**, dated May 9, 1876; application filed February 14, 1876.

To all whom it may concern:

Be it known that I, JOHN HENRY DANIELS, of New York city, in the county and State of New York, have invented a new and Improved Door and Window Fastener, of which the following is a specification:

My invention consists of a wedge-shaped fastener for fastening the door shut or open by wedging between the lower end and the floor, which is composed of a wedge between a bottom and top plate, the latter being jointed to the former near the apex of the angle, so that by removing the wedge from between the plates the top one will drop and free the door to let it close or open, and the bottom plate has a stud for pressing into the floor to prevent it from sliding.

Figure 1 is a perspective view of a partly-open door with my improved fastener under it. Fig. 2 is a side elevation of the fastener. Fig. 3 is a top view.

Similar letters of reference indicate corresponding parts.

A is the bottom, and B the top plate, of the fastener; C, the joint; D, the stud in the bottom plate for pressing into the floor, and E

the wedge for making up the complete form of the fastener by filling up the space between the plates. F is a ring in the head of the wedge for attaching a string for pulling out the wedge. By the use of this wedge the door can be unfastened by a person in bed, and the like.

The fastener may be used for holding windows partly open by wedging between the lower corner of the window and the jamb, or by pressing the stud into the upper sash the distance from the lower one it is desired to hold it; then, by putting in the wedge and raising the sash up, it will be fastened.

I am aware that door-fastenings have been made of two half-wedges hinged together at their small ends; but

What I claim is—

The combination, with a detachable one-piece wedge, of the plates A B, jointed at C, and held by stud D, as and for the purpose specified.

JOHN HENRY DANIELS.
